CLAIM

The ornamental design for a display screen or portion thereof with animated graphical user interface as shown and described.

DESCRIPTION

The patent or application file contains at least one drawing executed in color. Copies of this patent or patent application publication with color drawings will be provided by the Office upon request and payment of the necessary fee.

FIG. 1.1 shows a front view of the display screen or portion thereof with animated graphical user interface showing our new design;

FIG. 1.2 is a second image thereof; and

FIG. 1.3 is a third image thereof.

The appearance of the transitional image sequentially transitions between the images shown in Figs. 1.1-1.3. The process or period in which one image transitions to another image forms no part of the claimed design.

The broken line showing of a display screen or portion thereof with graphical user interface is included for the purpose of showing portions of the article which form no part of the claimed design. Portions within broken lines shown in stippled shading form no part of the claimed design. Text characters shown in broken lines form no part of the claimed design.
